FORM TOOL GRINDING FIXTURE

Harry Pelphrey, Detroit, Mich., assignor, by
mesne assignments, to Michigan Tool Com-
pany, a corporation of Delaware

Application May 7, 1930, Serial No. 450,501

2 Claims. (Cl. 125—11)

This invention relates to an improved fixture for guiding a grinding wheel shaping member.

The main objects of the invention are to provide an improved fixture of this kind for positioning a cutting member so as to form a predetermined curvature on the periphery of an abrasive wheel for grinding a forming tool there-by which is adapted to cut and shape the teeth on a hob; to provide improved means for shaping a grinding wheel so as to form a tool of this kind by which the teeth of a hob are conditioned to produce splines having radially offset sides on a shaft; to provide apparatus of this type in which a slight adjustment may be conveniently made for predetermining the width of the ultimate splines; and to provide improved means for compensating in the shaping of the contour of the grinding wheel for the clearance angle of the forming tool necessary to obtain proper cutting operation therewith.

An illustrative embodiment of my invention is shown in the accompanying drawings, in which—

Fig. 1 is a front elevation of a fixture embodying my invention.

Fig. 2 is a side elevation of the fixture shown in Fig. 1.

Fig. 3 is a plan view of the fixture.

Fig. 4 is a side elevation, partly in section, showing my improved fixture in an operative position.

Fig. 5 is a side elevation of a diamond cutting element holder.

Fig. 6 is a rear elevation of the holder shown in Fig. 5.

Fig. 7 is a fragmentary perspective view of a hob.

Fig. 8 is a perspective view of a hob forming tool.

Fig. 9 is a diagrammatic view, partly in section, illustrating the operation in which the teeth of the hob are cut by the forming tool.

Fig. 10 is a diagrammatic perspective view illustrating the operation in which the periphery of a grinding wheel is shaped to grind the hob teeth forming tool.

Fig. 11 is a diagrammatic front end view of the apparatus shown in perspective in Fig. 10, illustrating the locus of the cutting edge of the grinding wheel shaping element.

Fig. 12 is a perspective view of a splined end of a shaft.

The engagement between a hob and a spline shaft being cut thereby may be considered to include the same relative movements as exist between an interengaged worm and a worm wheel,

the worm wheel in such a case having straight and radially offset tooth side faces. If a true rolling action is to exist between the worm and wheel in such a case, the sides of the worm teeth must be formed to correspond in curvature to a cycloidal curve of predetermined generating radius.

Employing this as a basis it follows that if we form the side faces of a hob to the shape of a predetermined part of a cycloidal curve of proper generating radius, the hob will, in cutting a properly cooperating shaft, form thereon splines having straight and radially offset side faces.

Employing this as a basis the problem encountered is to shape a forming tool for shaping the hob teeth which forming tool will be provided with a cutting edge complementary in shape to the desired shape of the hob teeth. This presents a problem which I find may best be solved by grinding the tool to shape and accordingly, the present invention is primarily directed to a fixture for providing a grinding wheel with a contour complementary to the contour of the cutting edge of the forming tool (and therefore identical to the contour of the sides of the hob teeth) certain practical requirements being taken into consideration in carrying out these various steps such as, for instance, the inclination of the forming tool relative to the surface upon which it is working.

The fixture includes a support 1 having a base 2 on which a seat 3 is formed at an inclination with respect to the sides of the support and base. Formed on the upper side of the support 1 is a dovetail projection 4 which extends into a similarly shaped recess 5 in the lower side of a carriage 6 which is slidably mounted on the support 1. The recess 5 of the carriage is somewhat wider than the dovetail projection 4 of the support thereby providing a space between the adjacent rear sides of the recess 5 and projection 4 in which a gib 7 is located and secured against displacement by a bolt 8 having a lock nut 9 thereon. Mounted on the front side of the carriage 6 is a dust plate 10 which extends longitudinally of the carriage and support 1 and overlaps the upper edge portion of the front side of the support.

A tool holder or guide having a shaft 11 journaled in a laterally extending passage 12 formed in the carriage 6 is supported by the carriage and adapted to be shifted linearly therewith relative to the support 1 and base 2. Provided on the rear end portion of the shaft 11 is a pair of drums 13 and 14 on which the adjacent ends of

a pair of flexible metal straps or bands 15 and 16 respectively are secured, the strap 15 being wrapped in a clockwise direction on the drum 13 and the strap 16 being wrapped in a counter-clockwise direction on the drum 14. The outer end of the strap 15 is secured by a screw 16 in a clamping member 17 which is adjustably mounted by a bolt 18 on a bracket or support 19 at the left side of the fixture as viewed in Fig. 10 and the strap 16 is rigidly secured to a lug 20 on a bracket 21 mounted at the right end of the fixture. The straps 15 and 16 may be suitably tensioned by adjustment of the member 17 and nut 18. Rigidly mounted on the front end of the shaft 11 is a guide plate 22 having a guide bar 23 thereon which is adjustably held in a desired position by a bolt 24 extending through a slot 25 in the bar and threaded in an aperture in the plate 22.

In operation, the inclined lower side of the base 2 of the fixture is seated on the bed 26 of a machine which has a spindle 27, with the carriage 6 arranged to slide longitudinally of the bed substantially parallel to the spindle 27. A grinding wheel 28 is then rigidly mounted on the spindle 27 by which it is rotated about its normal axis of rotation as illustrated in Fig. 10.

A cutting tool comprising a shank part 29 having an aperture 30 in one side thereof in which is seated a cutting element 31 preferably having a diamond cutting point 32, is mounted for reciprocating movement on the guide plate 22 adjacent the edge of the guide bar 24. Formed in the end of the shank 29 is an aperture which communicates with the aperture 30 and in it is threaded a set screw 33 for firmly holding the cutting element 31 in axially adjusted position.

During rotation of the wheel 28, the guide plate 22 and shaft 11 are manually rotated about the axis of the shaft so as to change the position of the path of the cutting element 31 with respect to the wheel 28 and the cutting tool is held by hand against the guide plate 22 and guide bar 23 and manually reciprocated. This action subjects different portions of the wheel to the cutting action of the diamond point 32 which moves on various tangents to a cycloidal curve. When the guide plate is rotated in a counter-clockwise direction as viewed in Fig. 10, the inner end of the strap or band 16 is wound upon the drum 14 and the corresponding end of the band 15 is unwrapped from the drum 13. This action causes the carriage together with the guide plate supported thereon to be moved linearly to the right as viewed in Fig. 1.

The combined and related lineal and rotary movements of the shaft 11 and guide plate 22 cause the cutting point 32 of the element 31 to travel during its reciprocation in paths which are tangent to a cycloidal curve 34 such as would be developed by rolling a generating circle 35 on a straight line, the generating circle illustrated in Fig. 11 corresponding in diameter to the drums 13 and 14 on the shaft 11. The shaft 11 and guide plate 22 are manually rotated into desired position and the cutting tool is reciprocated while in engagement with the guide bar 23, thereby moving the cutting point 32 along a plurality of paths which are tangent to the cycloidal curve 34 as the guide plate is placed in various positions and the diamond point 32 dresses the side peripheral portion of the wheel 28 to a curvature which corresponds with the curvature of the cycloidal curve 34.

In this manner one side of the wheel 28 adjacent the periphery thereof is dressed so as to grind a curvature on the forming tool 36 shown in Fig. 8 which is complementary to the cycloidal curvature required and the side faces of the teeth 37 of the hob 38 illustrated in Fig. 7. Separate tools may be provided for forming the respectively opposite sides of the teeth 37, each tool being formed in the above manner or both faces of a tool of the form shown in Fig. 8 may be ground separately on the side cutting face of the wheel by first grinding one face; and then turning the tool through 180° about its longitudinal axis and applying the other face thereof to the wheel at an opposite inclination to the first grinding position.

In using the tool 36 to shape the side faces of the hob teeth, the tool is mounted on a conventional machine which is adapted to move it axially of its length as illustrated by the arrow 39 in Fig. 9, relative to a hob blank 40 during timed rotation of the latter. The extremity of the forming tool 36 may have a cutting edge 41 for dressing the metal between the bases of laterally adjacent teeth of the blank on the arcuate line 42 and may have a similar cutting edge 43 provided at the inner end of the cycloidal cutting edge 44 for correspondingly dressing the outer periphery of the teeth. The tool 36 is moved inwardly towards the center of the hob blank further at the rear end of each tooth than at the front end portion or cutting edge thereof so as to provide the usual clearance.

During the shaping of the teeth of the hob it is necessary to have the faces of the cutting tool 36 adjacent the cutting edges thereof at an inclination approximately 25 degrees to the surfaces upon which the cutting edges work, as indicated at 45 in Fig. 9. This angle is usually known as the clearance angle. In order to compensate, in the forming of the cutting surface of the grinding wheel, for the angular path of movement of the grinding wheel relative to a plane normal to the length of the forming tool in order to produce this clearance angle, the shaft 11 is positioned, by virtue of the inclined seat 3 of the base 2, at an inclination to the plane which includes the axis of the spindle 27 and the radius 27' of the wheel 28 with which the cutting point 32 registers as shown in Fig. 4, equal to the clearance angle.

The width of the spline that a hob cut by a forming tool ground in the above manner will produce may be predetermined by adjustably positioning the grinding point 32 of the cutting element 31 with respect to the shank 29 in which the latter is mounted. The distance between the point 32 and the dotted line 46 which extends through the axis of the shank 11 and is parallel of the guiding edge of the guide bar 23 is equal to one-half the width of the resulting spline.

With the above apparatus it is possible to move the cutting point of a tool along various paths which are tangent to an accurately developed cycloidal curve so that the curve forms the boundary on which the cutting surface of the grinding wheel is dressed. A hob tooth formed by a forming tool which has been ground on a wheel having a cutting surface of cycloidal curvature is capable of forming splines on a shaft having radial offset sides.

Formal changes may be made in the specific embodiment of the invention described without departing from the spirit or substance of the

broad invention, the scope of which is commensurate with the appended claims.

What I claim is:

1. In combination with a rotatable spindle having an abrasive wheel thereon for grinding a spinning hob forming member, a support, a rotatable tool guide shiftably mounted on said support, comprising a shaft, drums on said shaft, a pair of flexible bands each wound on one of said drums in an opposite direction relative to the other band and secured to said support for shifting said tool guide linearly during rotation thereof, and a reciprocating cutting tool on said guide, the cutting edge of said tool being retained by the related lineal and rotary movement of said guide in various paths which are tangent to a cycloidal curve.

2. A fixture including a support, a carriage shiftably mounted on said support, a tool holder journaled in said carriage having an exposed peripheral portion concentric with its axis of rotation and having a tool guiding member spaced from said axis, a cutting tool supported on said guiding member, and a band fixed at one end to said support and at its other end to said exposed peripheral portion for shifting said carriage and tool holder linearly in one direction transversely of the axis of rotation of the latter an amount equal to the circumferential travel of a point on said tool holder in an opposite direction during rotation thereof.
